UNITED STATES PATENT OFFICE.

RALPH F. YOURTEE, OF ST. LOUIS, MISSOURI.

WALL CONSTRUCTION.

1,297,960.

Specification of Letters Patent. Patented Mar. 18, 1919.

Application filed June 26, 1916, Serial No. 106,022. Renewed July 29, 1918. Serial No. 247,249.

To all whom it may concern:

Be it known that I, RALPH F. YOURTEE, a citizen of the United States of America, residing at St. Louis, State of Missouri, have invented new and useful Improvements in Wall Construction, of which the following is a specification.

This invention relates to wall construction and has for its object the provision of slabs 10 of such structural arrangement that they may interlock at their ends with similar slabs thus permitting the construction of a bin or the like without the use of mortar or plastic cement, the slabs being susceptible 15 of separation one from the other whereby the structure may be knocked down and transferred from one point to another if desired.

While the slabs are composed of like material and are of similar general configuration one slab is provided at its opposite ends with interlocking elements, ridges or grooves which are adapted to engage grooves or ridges provided at the ends of the adjacent 25 slabs. The slabs constitute sections of a vertical wall when assembled and the interlocking joint between the adjacent slabs occurs at the corners of the wall. Therefore, the slabs are provided with additional locking 30 means at their corner portions of the wall which prevent the adjacent sections of the wall from spreading.

In the accompanying drawings:—

Figure 1 is a perspective view of a portion 35 of a wall with the slabs disconnected from each other;

Fig. 2 is a fragmentary sectional view of adjacent slabs locked at a right angle to each other;

Fig. 3 is a similar view with the locked slabs disposed at an obtuse angle to each other;

Fig. 4 is a detailed perspective view of the end portion of one of the slabs;

Fig. 4^a is an under plan view of the slab shown in Fig. 4;

Fig. 5 is an under plan view of another of the slabs;

Fig. 6 is a fragmentary vertical sectional view of the connected slabs.

As illustrated in the accompanying drawings, the slabs A are intended to be set or laid upon the ground or a suitable foundation. Each slab A is provided at its opposite ends and at corresponding corners with

recesses 1, the said recesses extending a portion of the vertical height of the said slab. Each recess 1 is provided at its inner wall with a vertically disposed ridge 2, the said ridges extending the full vertical length of 60 the inner walls of the said recesses. It is to be understood that if desired the ridges shown and described in connection with the slab A may be replaced with grooves, it being optional whether the ridges or grooves 65 are applied to the slabs A and corresponding grooves or ridges applied to the other slabs hereinafter described.

The slab A is provided at its inner side and in the vicinity of its opposite ends with 70 ridges 3 which are located beyond the inner wall of the recesses 1 and which extend from the median line of the slab A to the upper walls of the said recesses as best shown in Fig. 4 of the drawing. The slab A is provided in the vicinity of its opposite ends with grooves 4 which are vertically aligned with the ridges 3. It is to be understood that if the ridges 3 and grooves 4 are employed upon the slab A corresponding 75 grooves and ridges are employed upon the slabs B and C and vice versa.

The slab A is provided at its upper edge with a longitudinally disposed groove 5 which terminates at its ends short of the 80 ends of the said slab. The said slab is further provided at its upper edge and in the vicinity of its ends with cross grooves 6 which lead in at the ends from the grooves 4 and at their other ends terminate short of 85 the outer face of the slab. The slab A is provided at the upper walls of its recesses 1 with cruciform ridges 7. (See Fig. 4^a.)

Each slab B is provided at its opposite ends with a recess 8 which extends a portion 90 of the way of the vertical height of the slab B. As shown in Fig. 1 the slab B is provided at the inner walls of the recesses 8 with grooves 9 adapted to receive the ridges 3 of the slab A when the said slabs are assembled. The said slab B is also provided at its inner side and in the vicinity of its opposite ends with grooves 10 which are located beyond the inner walls of the recesses 8 and which are adapted to receive the ridges 105 2 of the slabs A when the said slabs are assembled. The substitution of ridges for the grooves 9 and 10 may be made when the substitution of grooves for the ridges 2 and 3 upon the slab A is made. When the slabs 110

A and B are assembled and connected with each other they are disposed at angles with relation to each other and the locking joint occurs at the corner portions of the structure. The slab B is provided at the lower walls of its recesses 8 with cruciform grooves 11. The slab B is provided at its upper edge with a longitudinally disposed groove 12 which communicates at its ends with the 10 grooves 10. The cruciform grooves 11 of the slabs B are adapted to receive the cruciform ridges 7 of the slab A when the slabs are assembled. Each slab C is provided at its ends with recesses 13 there being provided 15 at the inner walls of the said recesses ridges 14. Each slab C is provided at its lower edge with a longitudinally disposed ridge 15 which communicates at its ends with the ridges 14. The ridge 15 of the slabs C which 20 is positioned above the slab B is received within the groove 12 of the slab B. The ridge 14 of the lowermost slab C supported upon the slab B is received in the groove 4 of the slab A. The slab C is provided at the 25 upper walls of its recesses 13 with cruciform ridges 16. The ridges 16 of the lowermost slab C supported upon the slab B are received in the end portions of the grooves 5 and 6 of the lowermost slab A. The slab C 30 is provided at its same side and in the vicinity of its opposite ends with grooves 17 which communicate at one end with portions of the cruciform ridges 16 as best shown in Fig. 5 of the drawing. The grooves 35 17 of the slabs C which are supported upon the slab B are adapted to receive the ridges 14 of the slabs C which are supported upon the slab A when the slabs are assembled. The slabs C are provided at their upper 40 edges with longitudinally disposed grooves 18 which at their ends terminate short of the ends of the said slab. The said slab C is further provided at its upper edge with grooves 19 which communicate at one end with the 45 grooves 17 and at their other ends terminate short of the outer face of the slab C. The grooves 19 are disposed transversely of the grooves 18 as best shown in Fig. 1 of the drawing. When the slabs C are assembled 50 one upon another the groove 18 of a lower slab receives the ridge 15 of the slab next above and the groove 19 of a slab C which is supported upon the slab B receives the

end portion of the ridge 15 of a slab C which is supported upon the slab A. 55

From the foregoing description taken in conjunction with the accompanying drawing it will be understood that when the slabs are assembled they form a strong and durable structure and that they interlock with each other without the necessity of mortar or plastic cement, consequently they may be readily taken apart and the structure may be transferred from one point to another. Also the structure is provided with strong 60 and durable interlocking corner joints whereby the structure may sustain considerable weight without danger of the slabs spreading or becoming disarranged in consequence of being subjected to such weight 65 or stress in any direction.

Having described the invention what is claimed is:—

A wall construction comprising a slab having one end cut away to form a horizontal extension and a vertical shoulder, the inner edge of said extension and said shoulder being provided with aligned grooves or ridges, the inner edge of said extension being further provided with a transverse horizontal 75 groove or ridge and the inner side of the extension being provided with a vertical groove or ridge aligning with said transverse groove or ridge, and a second slab of greater height than said first slab disposed at an 80 angle thereto and cut away to provide an extension and shoulder engageable with the shoulder and extension of said first named slab and having the inner edge of its extension and its shoulder provided with aligned 85 ridges or grooves engageable with said third and fourth named grooves or ridges, respectively, and having the inner edge of its extension further provided with a transverse ridge or groove engageable with said first 90 named groove or ridge, and the inner side of said second named slab being provided opposite its cut away portion with a vertical ridge or groove of the same length as and engageable with said second named groove 95 or ridge and further provided with a groove or ridge aligning with said last named ridge or groove and extending to the edge of the slab.

In testimony whereof I affix my signature.

RALPH F. YOURTEE.
